UNITED STATES PATENT OFFICE.

AMAND J. B. A. CHATAIN, OF NEW YORK, N. Y.

MARQUETRY.

SPECIFICATION forming part of Letters Patent No. 310,381, dated January 6, 1885.

Application filed April 27, 1883. (No model.)

To all whom it may concern:

Be it known that I, AMAND J. B. A. CHATAIN, of New York, in the county and State of New York, have invented a certain new and 5 useful Improvement in Mosaic Wood-Work, of which the following is a specification.

The object is to provide for manufacturing wooden mosaic work cheaply, for increasing its durability, and for enhancing its beauty.

In the accompanying drawings, Figure 1 is a face view of a piece of mosaic work made according to my improvement, and having a corner broken away to exhibit the construction. Fig. 2 is a transverse section of the same, 15 and Fig. 3 is a perspective view of a number of blocks which are formed in the manufacture of the mosaic work. Figs. 4, 5, and 6 represent different stages in the manufacture of my improvement.

Similar letters of reference designate corresponding parts in all the figures.

In manufacturing mosaic work I first saw sections of any desired width from the approximately-squared ends of pieces of wood crosswise of the grain. I next saw other sections from the approximately-squared ends of pieces of wood lengthwise of the grain. A sufficient number of these sections are then glued together in such manner that the grains 25

30 of alternate sections will run in the same direction, the whole forming a composite block. (More clearly shown in Fig. 4.) Crosswise

35 this block, or in a direction at right angles to the glued surfaces of the sections, and cross-

wise of the sections whose grains are length- 40

wise thereof, I saw other sections, of a thickness corresponding to that of the first sections, said sections being then composed of

45 strips or blocks A, alternate blocks having their grains running in the same direction, as more clearly

50 shown in Fig. 5. These second sections are then glued together in such manner that the grain of the wood in each strip or block A is on all sides transverse to that of the strips or

55 blocks next adjacent to it, (more clearly shown in Fig. 3,) and upon two opposite sides of the blocks showing the ends of the blocks A only the side of the grain is shown in any of the pieces composing it. The whole now forms

60 an approximate cube, from which I saw third sections of any desired thickness in a direction

transversely to the length of the blocks A, making the cuts in planes substantially parallel to the above-named two opposite sides. These last-named sections form complete tiles 55 composed of approximate cubes, as more clearly shown in Fig. 6, in which the grains of alternate cubes B run in the same direction, and the upper and lower surfaces of which show the grain running lengthwise of the wood. 60

Where patterns are to be produced in different woods, the boards will be selected of the desired woods, and the blocks cut from them will be arranged in such relations to each other that they will delineate the patterns. Even 65 when different woods are employed I prefer to arrange the blocks so as to reverse the grain. I deem this desirable not only because the beauty of the mosaic work will be enhanced, but also so that any shrinkage which may occur shall act in different directions throughout the mosaic work, and hence will not be so noticeable or so detrimental to the mosaic work.

By my improvement I am enabled to manufacture wooden mosaic work very cheaply, 75 to increase its durability, and to enhance its beauty. Mosaic work thus made can be used for furniture or floorings.

I do not here claim any particular means 80 for fastening the slabs together or to other articles, as various means may be employed for that purpose.

What I claim as my invention, and desire to secure by Letters Patent, is—

1. The method of manufacturing tiles of mosaic work, consisting in sawing sections from the approximately-squared ends of pieces of wood crosswise of the grain; sawing other sections from the approximately-squared ends of pieces of wood lengthwise of the grain; gluing these sections together in such manner that the grains of alternate sections will run in the same direction, the whole forming a composite block; sawing from this block in a direction 90 at right angles to the glued surfaces thereof and crosswise of the sections whose grains are lengthwise thereof other sections of a thickness corresponding to that of the first sections, said second sections being then composed of 95 strips or blocks A, alternate blocks having their grains running in the same direction;

gluing these second sections together in such manner that the grain of the wood in each strip or block A is on all sides transverse to that of the strips or blocks next adjacent to it, and upon the two opposite sides of the block which show the ends of the blocks A only the side of the grain is shown in any of the pieces composing it, the whole forming an approximate cube; sawing from this cube in a direction transverse to the length of the several pieces forming the cube, by making the cuts in planes substantially parallel to the above-named two opposite sides, other sections of any desired thickness, each of which sections is then composed of approximate cubes glued

together in such manner that the grains of alternate cubes run in the same direction, and the upper and lower surfaces of which show the grain running lengthwise of the wood, substantially as specified. 20

2. A mosaic tile consisting of approximately-rectangular pieces of wood glued together, the grain of each of which pieces of wood is transverse to that of those next adjacent, and the upper and lower surfaces of which show the grain running lengthwise of the wood. 25

AMAND J. B. A. CHATAIN.
